5 Claims. (Cl. 166—114)

The present invention is directed to multiple completion of wells. More particularly, the invention is concerned with completion of wells in a plurality of zones. In its more specific aspects, the invention has to do with apparatus for completion of wells in a plurality of zones. 10

The present invention may be briefly described as an apparatus for use in completion and workover of a well having its wall lined with a casing and perforated in a plurality of vertical spaced-apart zones. In the practice of the present invention, a problem exists where a plurality of tubing strings are employed to communicate with vertically spaced-apart zones in that the separate tubing strings tend to interweave or corkscrew in the well and bind with each other with varying degrees of tightness. Where the wells are completed according to the permanent well completion technique where the tubing strings are arranged permanently in place, it is difficult to remove the tubing strings once they are placed inasmuch as the corkscrewing or interweaving results in the tubing strings being held tightly together since one of the tubing strings is usually in compression in order to seal an upper packer which is usually employed. In some instances each of several tubing strings may be set in compression to seat a plurality of individual packers. With at least one of the tubing strings in compression, it is sometimes difficult, if not impossible, to remove the tubing strings when occasion demands. 15

In accordance with the present invention, the problem caused by corkscrewing and interweaving where multiple tubing strings are employed is solved by a particular arrangement of apparatus which allows completion and workover of a well. In this particular arrangement, a packing means having a single bore is placed between a lower formation and another formation; and then spaced above the packing means, a dual bore packing means is placed. Thereafter, the two tubing strings in tension are lowered either separately or together with their lower ends arranged above the packing means having the dual bores. With both tubing strings in tension, it is then possible to move them vertically when such becomes desirable. 20

However, another problem exists in that it is necessary to communicate with the several bores of the vertically spaced-apart packing means in order to obtain production from two or more hydrocarbon productive zones. This may be accomplished by bridging the space between one of the bores of the upper packing means and the lower end of one of the tubing strings with a tubular conduit which is supported by its upper end in the lower end of the tubing strings and sealed therein with its lower end extending into and protruding from the particular bore of the packer and sealed in said bore such that fluid may pass upwardly through the tubular conduit and to the tubing string for conductance into the wellhead. 25

The other tubing string also has a tubular conduit supported by its upper end in the lower end thereof and sealed such as to prevent passage of fluid past the tubular conduit and this tubular conduit is of sufficient length such that it extends through the other bore of the packing means and into and through the single bore of the lower packing means. Since the bores of the packing means are provided with sealing means, a seal is provided which allows fluid to be conducted from below the lower pack- 30

ing means through the tubular conduit and into the second tubing for flow to the wellhead.

This arrangement of apparatus also allows workover and servicing of the several zones penetrated by the well and also allows separate and simultaneous production from the several zones.

The invention will be further illustrated by reference to the drawing in which:

FIG. 1 is a sectional view illustrating a cased well in elevation perforated in a lower zone and having a packer set above the lower zone;

FIG. 2 is an illustration of perforations formed both in the lower zone and an upper zone with a second packer placed above the next highest zone;

FIG. 3 illustrates the running in of parallel eccentric tubings in tension and placement with their lower ends spaced vertically from the second packing means;

FIG. 4 is an illustration in section of the embodiment of FIGS. 1 to 4 with tubular conduits for production separately and simultaneously from two zones penetrated by the well;

FIG. 5 is an enlarged fragmentary cross-sectional view taken through the upper packing means of FIG. 2;

FIG. 6 is an enlarged fragmentary cross-sectional view taken through the lower packing means of FIG. 2;

FIG. 7 is an enlarged sectional view taken along the line 7—7 of FIG. 4.

FIG. 8 is a sectional view of apparatus for workover of the lower zone of FIGS. 1 to 4;

FIG. 9 is a partial sectional view of apparatus arrangement for workover of the upper zone of FIGS. 1 to 4;

FIG. 10 is an illustration of an embodiment in partial section of an apparatus arrangement for isolation of the two zones;

FIG. 11 is a fragmentary cross-sectional view of a modified lower packing means of FIG. 1; and

FIG. 12 is a fragmentary cross-sectional view of a modified upper packing means of FIG. 2 in which one of the bores of the upper packing means is larger than the other bore of the packing means.

Referring now to the drawing in which identical numerals will be employed to designate identical parts, numeral 11 designates a well drilled from the earth's surface, not shown, penetrating a plurality of hydrocarbon productive zones, sands, horizons, formations, strata, and the like, 12, 13, and 14. Arranged in the well 11 is a casing 15 which lines the wall of the well 11 and is cemented in place with cement 16. The casing is perforated in zone 14 by running a casing gun as may be desired and operating same to form perforations 17 in the zone 14. After the perforations 17 have been formed, a wire-line operated packer 18 such as one described at page 561 of the Composite Catalog of Oil Field and Pipe Line Equipment, 21st edition (1955—56), with a single bore 19 and further provided with sealing rings 20 is placed in the casing just above zone 14. After the packer 18 has been placed, a suitable casing gun, not shown, may be run and operated to form perforations 21 in the zone 13 and thereafter a packer 22 may be placed in the casing 15 as shown. 45

50 Alternatively and perhaps preferably, perforations 17 may be formed by using a through tubing gun after the tubing is set or in place in accordance with permanent well completion technique. This packer is provided with two parallel bores 23 and 24, the bore 24 being larger than the bore 23 and the bores 23 and 24 being provided, respectively, with sealing rings 25 and 26. The packer 22 may be a packer such as illustrated at page 849 of the Composite Catalog supra.

55 60 65 70 Parallel tubing strings 28 and 29 are then run in and placed in tension with their lower ends 30 and 31 spaced vertically above the packing means 22.

Since the lower ends 30 and 31 of the tubing strings 28 and 29 are a substantial distance above the packer 22 and since the packer 22 is spaced vertically from the packer 18, it is necessary to bridge the spaces in order that production may be had from the perforations 17 and 21. To accomplish production separately and simultaneously from the zones 13 and 14 as may be desired, tubular conduit 32 is lowered through the tubing 28 and supported in a landing nipple 33 provided in the lower end of the tubing 28 and sealed in the lower end of the tubing 28 by a sealing means 34 such that fluid may not pass between the outside of the tubular conduit 32 and the inner wall of the tubing 28. The lower end of the tubular conduit 32 is stabbed into the bore 23 of the packer 22 and is sealed therein by sealing means 25 with the tubular conduit 32 extending into the space A between the packing means 22 and 18 and allowing communication with the tubing 28 through the tubular conduit 32 with the perforations 21.

In order to establish communication for separate and simultaneous production of fluids from the zone 14, a second tubular conduit 35 is lowered through the tubing string 29 and supported on its upper end in the landing nipple 36 and sealed in the tubing string 29 by sealing means 37. The tubular conduit 35 extends through the bore 24 of the packer 22 and its lower end 38 is stabbed into the bore 19 of the packer 18.

As shown more clearly in FIGS. 6 and 7, the packer 18 has a bore 19 of a configuration different from the bores 23 and 24 of the packer 22; this is shown most clearly by reference to FIG. 6. In other words, the configuration of the lower end 38 of the tubular conduit 35 is such that it will not enter the bore 23 but will pass through bore 24 and conform in configuration to the bore 19 for passage therethrough.

The bores 23 and 24 of the packer 22 are sized differently and the configuration of the bore 19 of the packer 18 is different from the configuration of the bores of the first packing means but is sized such that the tubular conduit 35 will pass through one of the bores of the packing means 22 but will not pass through other of the bores of the packer 22 and will enter the bore 19 of the packer 18.

FIG. 8, a workover operation of the lower zone, will now be described and in this embodiment the tubular conduit such as 32 will remain in place in the tubing string 28 while the tubular conduit 35 will be suitably replaced by a modified tubular conduit 40 which is similar to the tubular conduit 38 excepting that it is formed to provide a concentric tubing 41 which defines an annular passageway 42 communicating with the space 49 above packer 22 by ports 43. Thus, in working over the zone 14 such as by injecting cement or a well treating fluid such as a surface-active agent, an acid, or the like, the fluid may be flowed downwardly through the tubing 29 and through the tubular conduit 40 and thence through the concentric tubing 41 to the zone 14 through the perforations 17 with the displaced fluid flow being through the annular passageway 42 out through port 43 and upwardly through the annular space 49 of the wellbore casing.

When it is desired to workover the zone 13, the tubular conduit 32 remains in place and another tubular conduit 32a, which may be identical except for the diameter thereof to the tubular conduit 32, is run into the tubing string 29 and supported on the landing nipple 36 and sealed therein with the sealing means 37a. It is then possible with this arrangement of apparatus to circulate fluid therein through the tubing 29 and through the tubular conduit 32a into the space A and upwardly through tubular conduit 32 to the wellhead through tubing 28.

Of course, in this embodiment, after removal of the tubular conduit 40, a plug means such as 45 would be lowered through the bore 24 of the packing means 22 and seated in the bore 19 of the packer 18 to isolate the lower zone 14 from the space A.

It may be desirable rather than having different configurations for the bores of the packer as shown in FIGS. 1-10 to have all the bores of the packers of cylindrical shape, and reference to FIGS. 11 and 12 shows that the modified bore 19a of packer 18 is smaller in size than the bore 24 of FIG. 12 while the bore 23 is still smaller in size than the bore 19a, thus allowing a tubular conduit of a size to fit the bore 19a to be placed through the bores 24 and 19a, but this tubular conduit may not enter the bore 23.

The present invention is quite advantageous and useful in that the problem of binding of tubing strings resulting from interweaving or corkscrewing is solved and it is yet possible to move the tubing strings such as 28 and 29 as desired for workover operations and, in fact, the two tubing strings may be removed as shown in FIG. 10 without contaminating the zones 13 and 14 by placing plugs such as 45, 46 and 46a in the bores 19, 24 and 23 of the packers 22 and 18, respectively. This allows the tubings 28 and 29 to be repaired in case of leakage due to corrosion or at the threads.

The several showings and the drawing are schematic and it will be understood that the usual pipe connections joining the several sections of the casings are omitted.

This is likewise true for the tubings 28 and 29.

By lowering tubular conduits such as 32, 35, 40 and 32a, it is unnecessary to align the packers 22 and 18 and tubing strings 28 and 29 in that, by virtue of the size or configuration of the bores of the packers and the size and configuration of the tubular conduits, it is not difficult to position a particular tubular conduit in the bore into which it is designed to fit. This may be accomplished by lowering the tubular conduit which is hanging by a wireline and which allows it to rotate until the tubular conduit fits into the bore into which it is designed to fit. It is not difficult to stab a tubular member into a bore since all that is necessary is to rotate the tubular member until it fits into the tubular configuration which is designed to accommodate it.

A plug member such as 45, 46 or 46a is similar to the special wire line plug for packers described in Serial No. 769,343, now patent 2,966,946, filed October 24, 1958, which discloses means to isolate a lower zone in a wellbore during operations to service or workover the upper zone which is above a separation packer in the casing.

In all figures of the drawing, it will be apparent that the upper ends of the tubular members 32, 35, 40 and 32a, as well as the upper ends of the plug members 46 and 46a, terminate in the well above the upper packer 22.

The nature and objects of the present invention having been completely described and illustrated, what I wish to claim as new and useful and secure by Letters Patent is:

1. Apparatus for use in completion and workover of a well having a casing arranged therein and perforated in a plurality of vertically spaced-apart zones which comprises two eccentrically arranged substantially parallel tubing strings suspended in tension throughout their lengths in said casing with their lower ends above said plurality of zones, a first packing means having two parallel bores arranged in said casing and spaced vertically below the lower ends of said tubing strings and above an upper of said zones, a second packing means having a single bore and arranged in said casing spaced vertically below the first packing means and below the upper and above a lower of said zones, a first tubular conduit supported by its upper end in the lower end of one of said tubing strings and provided with means for sealing with the inner wall of said one of said tubing strings of a length sufficient to extend into and through one of the bores of said first packing means, a second tubular conduit supported by its upper end in the lower end of the other of said tubing strings and provided with means for sealing with the inner wall of said other of said tubing

strings and of a length sufficient to extend into and through the other of the bores of the first packing means and through the bore of the second packing means, and means carried in the bores of said first and second packing means for sealing with the outer walls of said tubular conduit.

2. Apparatus for use in completion and workover of a well having a casing arranged therein and perforated in a plurality of vertically spaced-apart zones which comprises two eccentrically arranged substantially parallel tubing strings suspended in tension throughout their lengths in said casing with their lower ends above said plurality of zones, a first packing means having two parallel bores arranged in said casing and spaced vertically below the lower ends of said tubing strings and above an upper of said zones, said bores being sized differently, a second packing means having a single bore of a configuration different from the configuration of the bores of the first packing means and arranged in said casing spaced vertically below the first packing means and below the upper and above a lower of said zones, a first tubular conduit supported by its upper end in the lower end of one of said tubing strings and provided with means for sealing with the inner wall of said one of said tubing strings of a length sufficient to extend into and through one of the bores of said first packing means, a second tubular conduit supported by its upper end in the lower end of the other of said tubing strings and provided with means for sealing with the inner wall of said other of said tubing strings and of a length sufficient to extend into and through the other of the bores of the first packing means and through the bore of the second packing means, the lower end of the second tubular conduit having a diameter and a configuration conforming to that of the bore of the second packing means such that it will enter and pass through only one of the bores of the first packing means and will enter the bore of the second packing means, and means carried in the bores of said first and second packing means for sealing with the outer walls of said tubular conduits.

3. Apparatus for use in completion and workover of a well having a casing arranged therein and perforated in a plurality of vertically spaced apart zones which comprises two eccentrically arranged substantially parallel tubing strings suspended in tension throughout their lengths in said casing with their lower ends above said plurality of zones, a first packing means having two parallel bores arranged in said casing and spaced vertically below the lower ends of said tubing strings and above an upper of said zones, the bores of said first packing means being of different size, a second packing means having a single bore of a size no greater than that of the larger of the bores of said first packing means, and arranged in said casing spaced vertically below the first packing means and below the upper and above a lower of said zones, a first tubular conduit supported by its upper end in the lower end of one of said tubing strings and provided with means for sealing with the inner wall

of said one of said tubing strings of a length sufficient to extend into and through the smaller of the bores of said first packing means, a second tubular conduit supported by its upper end in the lower end of the other of said tubing strings and provided with means for sealing with the inner wall of said other of said tubing strings and of a length sufficient to extend into and through the larger of the bores of the first packing means and through the bore of the second packing means, the diameter of said second tubular conduit being sufficiently large to pass only through the larger of the bores of said first packing means and through the bore of the second packing means, and means carried in the bores of said first and second packing means for sealing with the outer walls of said tubular conduits.

4. Apparatus in accordance with claim 3 in which the single bore of the second packing means is of a size the same as that of the larger of the bores of the first packing means.

5. Apparatus for use in completion and workover of a well having a casing arranged therein and perforated in a plurality of vertically spaced-apart zones which comprises two eccentrically arranged substantially parallel tubing strings suspended in tension throughout their lengths in said casing with their lower ends above said plurality of zones, a first packing means having two parallel bores arranged in said casing and spaced vertically below the lower ends of said tubing strings and above an upper of said zones, a second packing means having a single bore and arranged in said casing spaced vertically below the first packing means and below the upper and above a lower of said zones, a first tubular conduit supported by its upper end in the lower end of one of said tubing strings and provided with means for sealing with the inner wall of said one of said tubing strings of a length sufficient to extend into and through one of the bores of said first packing means, a second tubular conduit supported by its upper end in the lower end of the other of said tubing strings and provided with means for sealing with the inner wall of said other of said tubing strings and of a length sufficient to extend into and through the other of the bores of the first packing means, the lower section of said second tubular conduit being formed with a concentric inner tube providing an annular passage fluidly communicating with the space in the wellbore above the first packing means by a port in the outer wall of said second tubular conduit, and means carried in the bores of said first and second packing means for sealing with the outer walls of said tubular conduits.
